UNITED STATES PATENT OFFICE.

WILLIAM F. MOON, OF MILWAUKEE, WISCONSIN.

YARN-SPECK REMOVER.

1,325,528.

Specification of Letters Patent. Patented Dec. 23, 1919.

Application filed June 6, 1919. Serial No. 302,136.

To all whom it may concern:

Be it known that I, WILLIAM F. MOON, a citizen of the United States, and resident of Milwaukee, in the county of Milwaukee and 5 State of Wisconsin, have invented new and useful Improvements in Yarn-Speck Removers, of which the following is a description, reference being had to the accompanying drawings, which are a part of this specification.

The present invention relates to a device for removing lumps of fiber or what are commonly called "specks" from yarn or thread, previous to its use in a spinning or 15 weaving machine.

An object of this invention is to provide a device of this character which will include means for positioning the speck, and means co-acting with the positioning means to 20 sever the speck from the thread.

With the above and other objects in view which will appear as the description proceeds, my invention resides in the novel construction, combination and arrangement 25 of parts substantially as hereinafter described and more particularly defined by the appended claims, it being understood that such changes in the precise embodiment of the hereindisclosed invention may be made 30 as come within the scope of the claims.

In the accompanying drawings, I have illustrated two complete examples of the physical embodiment of my invention constructed according to the best modes I have 35 so far devised for the practical application of the principles thereof, and in which:

Figure 1 is a side view of one form of my invention, parts being broken away to more clearly illustrate the details of construction.

Fig. 2 is a top plan view of one end of my invention.

Fig. 3 is a view, part in section and part in elevation, said view being taken on the 45 line 3-3 of Fig. 1.

Fig. 4 is a view taken transversely through the supporting frame of my device, the reciprocating cutting member being removed.

Fig. 5 is a perspective view of one of the reciprocating cutting members attached.

Fig. 6 is a side view of a modified construction of speck remover embodying the principles of my invention, said view having parts broken away and in section to

more clearly illustrate the details of construction.

Fig. 7 is a top plan view thereof, parts being broken away and in section for the purpose of illustrating details of construction. 60

Fig. 8 is a side view of one end of the device, parts being broken away and in section, and

Fig. 9 is a view, part in section and part 65 in elevation, said view being taken on the line 9-9 of Fig. 6.

Referring now to the drawings, and more particularly to Figs. 1 to 5 inclusive, the numeral 10 designates generally the frame 70 of the machine which has a plurality of pairs of upstanding spaced apart yoke shaped standards or arm members 11; 12 a pair of drive shafts mounted in the frame and provided with a pair of meshed gears 75 13, and 14 a pulley driven from any suitable source of power and adapted to rotate the shafts 12.

In the drawings, I have illustrated a plurality of speck removing devices, each of 80 which successively acts upon the thread to remove any specks therefrom, so that if the first device does not remove the speck, it will be removed by another of the devices.

Each of these speck removing devices is 85 mounted in the adjacent yoke members 11, and consist generally in means for presenting the speck in a position in which it may readily be severed from the thread or yarn by the cutters or shears hereinafter described.

The means for presenting the speck in position for removal consists of a bed-block 15 secured to the frame 10 by means of a screw 16 intermediate the yoke members 11 95 as best shown in Fig. 4. The bed block 15 is in the form of a stationary knife and co-acts with the reciprocating cutting means, to be later described. The yarn or thread 17 is guided through the frame member 10 100 by means of suitable guiding members 18 and 19, located at each end of the frame, and the thread, in its passage through the frame engages the top of the bed block, and should the speck be on the under side of the 105 yarn, the same will be turned or positioned to the side, there to be severed from the thread as will be later described.

As the bed block 15 is insufficient in itself to retain the thread upon its top surface, in 110

that the thread would become disengaged therefrom, as will be obvious, I so construct my cutting means as to coöperate with the bed block to retain the thread in engagement 5 with its top surface which is essential to insure the positioning of the speck. The cutting means consists of a pair of vertical knives 20 disposed one on each side of the bed block 15, and each secured to the top 10 of a block 21 by directing the upper end thereof laterally as at 22, and securing the same by means of fastenings 23. Each knife 20 has formed on its lower end a slightly inclined shearing edge 24 which terminates 15 in a depending lug or ear 25 which provides the means for retaining the yarn upon the bed block 15, irrespective of the position of the knife.

In order that the knives may be resiliently urged to engagement with the bed block 15, each block 21 is urged outwardly from its retainer 26 by means of an extensible spring 27, confined therein and impinging against the block 21. The movement of 25 the block 21 on the spring 27 is limited by means of a bolt 28 which has one end thereof in threaded engagement with the block 21 and the other end thereof projecting outwardly of the retainer 26 and provided with 30 locking nuts 29. The portion of the bolt 28 disposed in the retainer 26 is capable of movement therein as will be obvious, and the bolt 28 provides the means for semi-rigidly securing the knife 20 with the retainer 26.

The retainer 26 is slidably confined between the adjacent yoke members 11 and removably retained in position by means of a removable plate 30 which, with the laterally projecting flanges 31 formed on the yoke members 11, provides guiding means for the retainer 26. The retainer 26 is adapted to be reciprocated by means of a cutting rod 32 having its upper end journaled between a pair of spaced depending ears 33 carried by the retainer 26, and its lower end provided with bearings 34 and journaled by an eccentric 35 fixed to the adjacent shaft 12.

As the shaft 12 is rotated, a reciprocating movement will be imparted to the retainer 26 and consequently its knife 20, whereby the knife will, with the bed block 15, sever the speck which may be positioned to the side by the bed block 15 from the thread. 55 The opposed eccentrics 35 on the shafts 12 are so arranged that the knives 20 of each pair will be oppositely reciprocated in order that a continuous cutting action is obtained throughout the entire passage of the yarn or thread through the machine. The eccentrics 35 are also arranged in order that the cutting knives on one side of every other pair of cutting means will be operated in unison. 60

As the thread passes through the machine, 65 it is successively acted upon by the plurality

of pairs of cutting means, and the thread is continuously guided upon the bed block by means of the depending lugs 25 which will be of sufficient length to insure the engagement of the same with the bed block 15 when 70 the knife 20 is at its forward limit of movement. Thus the thread 17 is also guided through the frame by the depending lugs 25 as well as by the members 18 and 19.

By providing a plurality of speck removing devices, the complete removal of specks from the yarn is assured, for as will be understood by those skilled in the art to which an invention of this character appertains, the yarn, owing to the tension which it is 80 under, turns throughout its passage through the machine by reason of its being twisted and woven, and so should a speck be upon the upper surface of the yarn when it passes over the first bed block 15, the yarn will 85 have turned during its passage through the short distance between the first bed block and the second, and thus the speck will be presented to the bed block. When the speck is presented to the bed block, it is naturally 90 moved or positioned to one side and thus severed from the thread when the knife 20 descends.

Referring now more particularly to Figs. 6, 7, 8 and 9, I employ the same principles 95 as hereinbefore described, by using a plurality of pairs of rocking members in place of the reciprocating members 20. This form of my invention comprises generally a longitudinal frame member 36 having 100 formed thereon a plurality of opposed pairs of spaced upwardly extending centrally apertured lugs or ears 37, and to each ear 37 is pivotally secured a rocking arm 38 by means of a pivot bolt 39 having its inner 105 end in threaded engagement with the aperture of the ear 37.

The rocking arms 38 disposed on one side of the frame 36 are adapted to be rocked by means of a pitman 40 pivotally secured as 110 at 41 to a connecting rod 42 having pivoted thereto as at 43, the lower ends of the rocking arms 38 disposed on one side of the frame 36, whereby all of the arms 38 on one side of said frame will be rocked in unison. The pitman 40 is oscillated by means of an eccentric 44 carried by a shaft 45 adapted to be rotated by a pulley 46 connected with any desired source of power. 115

As best shown in Fig. 7, the rocking arms 120 38 disposed on the other side of the frame 36 are also connected in a like manner by means of a connecting rod 42 and pitman 40. As best shown in Fig. 8, the eccentrics 44 are so positioned on the shaft 45 as to insure the 125 oppositely rocking of the arms 38 of each pair whereby a continuous cutting movement is effected.

The upper end of each rocking arm 38 is formed with a cylinder or centrally aper- 130

tured cap 47 in which is slidably mounted a hollow sleeve end 48 of a retaining block 49. The retaining block 49 is normally urged downwardly or outwardly of the cylinder 47 by means of an extensible spring 50 disposed in the central bore of the sleeve 48 and having its upper end impinged against a plate 51 engaging the lower end of a tension adjusting screw 52. Secured to the inner face 10 of the retainer 49 by means of a screw 53 is a rocking knife member 54 which has its lower end yieldingly held in engagement by means of the spring 50 with a bed block 55 secured to the frame 36 intermediate an opposed pair of ears 37 by means of a screw 56.

The pivot 39 of the arm 38 has its center in alinement with the top surface of the bed block 55 to insure the constant engagement of the knife 54 with the bed block 55 when 20 the knife is rocked. As before described, the knives of each opposed pair are oppositely rocked and a continuous cutting action is had. The yarn 17, as in the other form of my invention is guided through the frame 36 25 by means of guiding members 18 and 19, and also by means of the knives 51 and bed block 55.

The opposed pairs of knives 54 are spaced apart exactly the thickness of the thread, 30 and as the thread passes over the bed block 56, the speck, if it is on the under side of the thread, will be moved or positioned to one side and there severed by means of the knives 54 when they are rocked. The yarn 35 is successively acted upon by each pair of cutting means as in the other form of my invention, and consequently further description thereof is thought unnecessary.

From the foregoing description, it would 40 be apparent that the rocking members 54 serve to, in a sense, crush the speck from the yarn, and to insure this crushing action, the spring 50 is adjusted to the proper tension by means of the adjusting screw 52.

45 What I claim as my invention is:

1. In a yarn speck remover, the combination of a bed block for positioning the speck, and means co-acting with the bed block to provide shearing means for cutting the 50 speck from the yarn.

2. In a yarn speck remover, the combination of a bed block for positioning the speck, and means co-acting with the bed block to

provide means for cutting the speck from the yarn.

55

3. A yarn speck remover comprising means for guiding a thread, a cutting member, and means co-acting with the cutting member to provide means for positioning a speck on the thread to one side and then severing the 60 speck therefrom.

4. In a yarn speck remover, the combination of means for positioning a speck on the 65 yarn, and a movable cutting member co-acting with the positioning means to sever the speck from the yarn.

5. A yarn speck remover comprising means for guiding a thread, a bed block for turning the thread to position a speck to either side, and a cutting member co-acting with the bed 70 block to sever the speck from the thread as it advances through the guide means.

6. In a yarn speck remover, the combination of means for guiding the thread, a bed block for turning the thread to bring the 75 speck to either side, and a pair of cutting members co-acting with the bed block to sever the speck from the thread as it advances through the guide means.

7. In a yarn speck remover, the combination of means for guiding the thread, a bed block for positioning the speck and provided with opposed shearing edges, and reciprocating means co-acting with the shearing edges of the bed block to sever the speck from the 85 thread as it is guided therethrough.

8. In a yarn speck remover, the combination of means for guiding the thread, a bed block for positioning the speck and provided with opposed shearing edges, and a pair of 90 oppositely reciprocating cutting members co-acting with the shearing edges of the bed block to sever the speck from the thread as it is guided therethrough.

9. In a yarn speck remover, the combination of means for guiding the thread, a plurality of bed blocks provided with shearing edges, said bed blocks acting to position the speck to either side, and a plurality of pairs of oppositely reciprocating cutting members 95 co-acting with the shearing edges of the bed block to sever the speck from the thread as it is guided therethrough.

In testimony whereof, I affix my signature.

WILLIAM F. MOON.
